INVENTOR

Charles E. Langmaid,

UNITED STATES PATENT OFFICE.

CHARLES E. LANGMAID, OF MIDDLEBOROUGH, MASSACHUSETTS, ASSIGNOR
OF ONE-HALF TO HORATIO BARROWS, OF SAME PLACE.

BUTTON-HOLE-CUTTING MACHINE.

SPECIFICATION forming part of Letters Patent No. 252,781, dated January 24, 1882.

Application filed October 31, 1881. (No model.)

To all whom it may concern:

Be it known that I, CHARLES E. LANGMAID, of Middleborough, in the county of Plymouth and State of Massachusetts, have invented new and useful Improvements in Button-Hole-Cutting Machines, of which the following is a specification.

My invention relates to devices for stopping and starting the cutting-die of a power-machine, and has for its object the controlling of the movement of the die, so that but a single hole shall be cut by it at each movement of the foot-lever which starts and stops the machine. This object is attained by the mechanism illustrated in the accompanying drawings, in which—

Figure 1 is a side elevation of my machine, the driving-pulley and clutch device of which are shown in the position which they occupy when the working part of the machine is not in operation. Fig. 2 shows in elevation a part including a clutch device, the parts of which are shown in the position that they occupy when the machine is in motion. Fig. 3 is a section taken on line X Y of Fig. 1, showing some of the parts in rear elevation. Fig. 4 is the same as Fig. 3, except that some of the parts are shown in different positions.

In the drawings, A A' A² A³ A⁴ represent the casting which constitutes the body and frame-work of my machine.

B is the die which serves to cut the button-hole, and is attached to a vertically moving rod, B'. The die B cuts onto the adjustable block C, this block being held in place by the screw C' and adjusted vertically by the screw C², Fig. 1. The bar B' is operated by a crank, B⁵, on the crank-disk B⁶, the action being communicated by the link B⁴ and pin B³, which projects from the sleeve B², which is firmly clamped to the bar B' by the screw b, as shown in Fig. 1. The crank-disk B⁶ is attached to the main shaft B⁷ B⁸, which receives its motion from the driving-wheel B⁹ whenever the said driving-wheel is moved forward, so that the parts of the clutch device engage one with another, as will be hereinafter explained.

D is a disk rigidly attached to the driving-shaft B⁷ B⁸, and has upon its face a cylindrical portion, D', and a face-cam, D², also a socket,

(shown at D³, Figs. 3 and 4.) This socket at D³ serves as a recess for the entering of the upper end of the locking-pin E, said pin E being shown in position in Figs. 1 and 3, that being the position it occupies while locking the operative part of the machine. The locking-pin E slides vertically in a housing, E' E². (Shown in elevation in Fig. 1.) This locking-pin E is forced upward by means of a spring, e', the lower end of which rests upon a part, E³, of the housing E', while the upper end reacts against a collar, e, which is made fast to the locking-pin E by means of a set-screw, e², the tendency of the spring being to throw the locking-pin E upward.

The housing E' E², which carries the locking-pin E, has a shank, F, extending laterally through the boss A³ and into a hole made at A⁵ in the frame of the machine, as shown in Fig. 1. This construction allows of a horizontal movement of the housing E' and all of its attached parts, the movement being parallel to the shaft B⁷ B⁸. This movement is influenced in one direction—that is, toward the front of the machine—by means of the spring F', one end of the spring F' resting against the fixed boss A³, while the other end reacts against a collar, F², which is fastened to shank F by means of a set-screw, F³, so that the tendency of the spring is to draw the housing E' toward the front of the machine.

The collar F² is flat on its under side and rests and slides upon the flat surface of the projection A², (see Fig. 1,) so that neither the shank F nor the housing E' E² can turn about the axis 85 of the shank F. The upper and rear end, E², of the housing E' E² terminates in a clutch-fork, E⁶, the bifurcations of which are in a groove formed in that part of the clutch marked H, Fig. 1, so that any longitudinal movement of the housing E' E² causes a corresponding longitudinal movement of the clutch H and the driving-wheel B⁹ on the shaft B⁷ B⁸.

D⁴, Figs. 1, 3, and 4, is a stop or buttress attached to the cylinder D', and serves to engage 91 with the stop H² on the part of the clutch H, so that whenever the part H is moved forward to the position shown in Fig. 2 then the stops H² and D⁴ will engage one with the other, and thus the motion of the driving-wheel B⁹ will 11

be communicated to the operating part of the machine.

- The locking-pin E has a fillet, E⁶, on it, (see Figs. 3 and 4,) the uppersurface of which serves 5 as a shoulder for the arms L L to catch upon. (See Fig. 3.) These arms L L are hinged at the points L' L' to an upright bar, L³ L⁴, the said bar L³ L⁴ being connected to a foot-lever, by which it is operated by the user of the machine.
- 10 The upper part of this bar L³ L⁴ is made hollow, so that it may slide up and down on the lower end of the lock-pin E.

The pins K K, Figs. 1, 3, and 4, are stationary, as shown, and serve to throw out the arms 15 L L against the pressure of the springs L² L², so as to disengage them from the fillet E⁶ on the lock-pin E when the said lock-pin E has been drawn down by them sufficiently far to clear it from the socket in the cam-disk D. As 20 soon as this lock-pin E is withdrawn then the spring F', Fig. 1, will draw the housing E' E², and with it the lock-pin E, forward to the position indicated in Fig. 2. This motion of the housing E' E² will, acting through the fork E⁶, draw 25 the clutch H forward, so that the stops H² and D⁴ will engage with each other and start up the machine. This motion of the machine will continue until the shaft B⁷ B⁸ has nearly made one revolution. When the face-cam D² comes in contact with the lock-pin E (said lock-pin E having in the meantime moved vertically upward.) 30 it forces it, together with the housing E' E², backward, thus causing the clutch-stop H² to

disengage with the stop D⁴, and just at the time of this disengagement the pin E springs forward into the recess D³ made in the disk D, and thus stops the machine at the end of its first complete revolution, so that in no case can the machine cut more than one button-hole without automatically stopping itself. This 40 action is made certain by the construction and arrangement of the parts already described—namely, the arms L L, their springs L² L², and the upright bar L³ L⁴, which, in connection with the foot-lever, serve to draw down the 45 lock-pin E, since by this arrangement it is impossible for the operator to hold the lock pin E away from the notch in the cam, the operator being enabled to withdraw the pin from the catch, but not to retain it, as the stationary 50 pins K K automatically throw off the arms L L, and thus release the lock-pin E at once, it being impossible for the operator to hold the lock-pin down.

I claim—

In a button-hole-cutting machine, the combination of the clutch device and the lock-pin E with the lock-pin-withdrawing device, consisting of the arms L L, springs L² L², bar L³ L⁴, and stationary throw-off pins K K, all operating together substantially as described, and 55 for the purpose set forth.

CHARLES E. LANGMAID.
